Patented Jan. 10, 1922.

Inventor,
John L. Brown,
By Henry F. Spivington,
Attorney.

UNITED STATES PATENT OFFICE.

JOHN L. BROWN, OF CATONSVILLE, MARYLAND, ASSIGNOR OF ONE-TENTH TO CHARLES W. SMILEY, ONE-TENTH TO JAMES COHEN, AND ONE-TENTH TO GRAFTON L. ROGERS, ALL OF BALTIMORE, MARYLAND.

INDUCTION FURNACE.

1,402,832.

Specification of Letters Patent. Patented Jan. 10, 1922.

Application filed December 22, 1920. Serial No. 432,563.

To all whom it may concern:

Be it known that I, JOHN L. BROWN, a citizen of the United States, residing at Catonsville, in the county of Baltimore and State of Maryland, have invented certain new and useful Improvements in Induction Furnaces, of which the following is a specification.

This invention relates to a process of and an apparatus for heating metals by means of an electric current, and its object is to accomplish this in a novel and improved manner as will be pointed out in detail hereinafter.

Briefly stated, the invention consists in an electrically conductive coil connected to an alternating current source, inside of which coil is positioned a crucible or other suitable holder for an electrically conductive material to be heated or reduced. The current flowing through the coil, sets up, by induction, a secondary current in the contents of the crucible, and the heat evolved by such secondary current accomplishes the reduction of the contents of the crucible. The present invention is distinguished from previous apparatus of this type in that the coil is molten metal, the same being caused to flow in a helical channel formed in a mass of refractory material, and surrounding the crucible. The apparatus can therefore be used for melting metals by the direct passage of an electric current therethrough, and also for reducing other metals in a crucible by an induced current obtained by the passage of the primary current through the first mentioned batch of metal, the same taking the form and function of the primary winding of an induction coil.

In order that the invention may be better understood, reference is had to the accompanying drawing forming a part of this specification, in which a sectional and diagrammatic view of the apparatus is shown.

Referring specifically to the drawing, 5 denotes a support for a crucible or similar container 6 for the material to be heated, said support being provided with a chamber 7 in which the crucible seats. The support, as well as the crucible, are constructed of a suitable refractory and electrically non-conducting material.

In the support 5 is also embedded a hollow coil 8 of some fusible and electrically conductive material which surrounds the chamber 7. One end of the coil projects from the top of the support and is here fitted with a hopper 9, the same opening into the interior of the coil. The bottom of the coil extends from the bottom of the support 5, and it is here provided with a gate 10 for closing said end.

The coil 8 is adapted to be filled with granular or comminuted metal, as shown at 11, the same being supplied from the hopper 9.

At 12 is shown an alternating current source one side 13 of the circuit being connected to one end of the coil 8, and the other side 14 of the circuit being connected to the other end of the coil. Where the circuit connections are made, the coil is provided with water jackets 15 having suitable inlet and outlet connections 16 and 17, respectively.

As already stated, the apparatus is designed for melting or heating metal in the crucible 6, the same being shown at 18, and also to melt the contents 11 of the coil 8, the operation being as follows:

The coil 8 and its contents 11 are to all intents and purposes the primary winding of an induction coil, and hence when an alternating current is flowing therethrough, a current is induced in the electrically conductive contents 18 of the crucible 6. The heat developed by the induced secondary current accomplishes the reduction of the contents of the crucible.

Initially the closely packed particles of the electrically conductive filler 11 of the hollow coil 8 are in a solid state, but the heat developed by the passage of the exciting current therethrough is sufficient to cause said particles to melt. The retaining wall 8 for the metallic particles 11 also melts, and hence there is now left in the supporting member 5 a helical passage containing molten metal, and upon opening the gate 10 and continuing the supply of material to this passage, there is maintained a constant discharge of molten metal from the lower end of the passage. It will be understood that melting of the upper and lower projecting

ends of the coil 8, where the connections with the current supply mains 13 and 14 are made, is prevented by the water jackets 15, so that the inlet and the outlet of the helical passage formed in the body 5 remain intact. The coil 8 will be made of any fusible material, and when the same and its contents 11 melt the wall of the helical passage formed in the body 5 of refractory material calcines 10 so as to produce a solid retaining wall for the fluid metal. The flow of the current is not interrupted when the filler 11 assumes a molten state, and hence the primary of an induction coil is now had which is a fluid 15 metal. The material preferably employed for the body 5 is zirconium oxide.

I claim;

1. The process of heating electrically conductive material consisting in placing such 20 material in an electrically non-conductive container surrounded by a primary winding of fusible material interposed in an energizing circuit, providing such fusible material with a helical channel through which it is 25 free to flow when it obtains a molten state, providing for the escape of the molten material from the channel, and adding fresh material to maintain the continuity of the flow.

2. The process of heating electrically conductive material consisting in placing such 30 material in an electrically non-conductive container surrounded by a primary winding of fusible material, connecting such fusible material to an energizing circuit to melt the same and produce a primary winding consisting of molten material, and adding fresh material to maintain the continuity of the winding.

3. The process of heating electrically conductive material consisting in placing such 40 material in an electrically non-conductive container, and utilizing the heating effect of a secondary current induced in the material by a primary winding consisting of molten material surrounding the container and connected to an energizing circuit, and constrained to flow in a helical course.

4. The process of heating electrically conductive material consisting in placing such 50 material in an electrically non-conductive container, and utilizing the heating effect of a secondary current induced in the material by a primary winding consisting of molten material surrounding the container and connected to an energizing circuit, and constrained to flow in a helical course, and adding to the material to maintain the continuity of the flow.

5. An electric metal heating process consisting in passing an electric current through a batch of metal to melt the same, said batch being arranged helically, providing a channel for the flow of the molten metal, providing for the escape of the molten metal from

the channel, adding to the batch to maintain 65 the continuity of the flow of molten metal, and by induction from the current through the molten metal heating another and different batch of metal.

6. An electric metal heating process 70 consisting in passing an electric current through a batch of metal to melt the same, said batch being arranged helically, providing a channel for the flow of the molten metal, providing for the escape of the molten metal from 75 the channel, adding to the batch to maintain the continuity of the flow of molten metal, and utilizing the current flowing through the molten metal to heat by induction an electrically conductive material. 80

7. An electric metal heating process consisting in passing an electric current through 85 a batch of metal to melt the same, said batch being arranged helically, providing a channel for the flow of the molten metal, providing for the escape of the molten metal from the channel, adding to the batch to maintain 90 the continuity of the flow of molten metal, and utilizing the current flowing through the molten metal to heat by induction an electrically conductive material, around which the molten metal traverses and from which it is electrically insulated.

8. In an electric heating apparatus, a body 95 of refractory and non-conductive material provided with an internal passage in the form of a helix and having a chamber within the helix, a container for an electrically conductive material to be heated positioned in the chamber, a fusible lining for the 100 helical passage, a filler for the passage composed of a fusible electrically conductive material, means for passing an electric current through the filler to melt the same, means for permitting escape of the molten 105 material from the passage, and means for adding fresh material to maintain the continuity of the flow of molten material.

9. In an electric heating apparatus, a body 110 of refractory and nonconductive material provided with an internal passage in the form of a helix, and having a chamber within the helix, a container for an electrically conductive material to be heated positioned in the chamber, a filler for the passage 115 composed of a fusible electrically conductive material, means for passing an electric current through the filler to melt the same, means for permitting escape of the molten material from the passage, and means for 120 adding fresh material to maintain the continuity of the flow of molten material.

10. In an electric heating apparatus, a body of refractory and non-conductive material, a hollow coil of fusible material embedded in said body and projecting therefrom at its ends, one of the projecting ends of the coil having a material inlet and the

other end having an outlet, a filler of fusible electrically conductive material in the coil and adapted to enter the same through the inlet, means for passing an electric current 5 through the coil and its filler, the current connection being made at the projecting ends of the coil, cooling means associated with

10 said ends for preventing fusing thereof, the aforesaid body having a chamber located axially within the coil, and means for supporting in said chamber a batch of electrically conductive material.

In testimony whereof I affix my signature.
JOHN L. BROWN.
